UNITED STATES PATENT OFFICE

ROY E. HAMILTON, OF KANSAS CITY, KANSAS, ASSIGNOR TO LOCK JOINT WINDOW COMPANY, OF KANSAS CITY, MISSOURI, A CORPORATION OF DELAWARE

WINDOW PULLEY

Application filed July 25, 1930. Serial No. 470,682.

This invention relates to window pulleys and has for its primary object the provision of an especially constructed housing for supporting the wheel of the pulley, which housing is formed to present a plurality of feet, all of which are struck from the sides of the metal housing in such a manner as to provide a three-point support which allows the structure to be used as an overhead pulley in the manufacture and installation of vertically 10 slidable window frames.

One of the salient features of the invention is to provide an overhead window pulley which has a housing provided with a plurality 15 of supporting feet, one of which is long enough to receive a fastening means at a point sufficiently removed from the housing to permit the use of power driven tools for placing such fastening means.

20 A yet further object of the instant invention is the provision of a novelly and cheaply constructed housing for window pulleys, one side of which has struck therefrom a pair of supporting feet, the other side having a single 25 foot projecting therefrom; all of said feet being disposed in the same plane and spaced inwardly from one edge of the housing.

An even further object of this invention is the contemplation of a window pulley housing 30 which has a supporting foot projecting laterally from one side thereof in a plane spaced inwardly from one edge of the housing, said foot being of a projected length substantially greater than the distance it is 35 spaced inwardly from the aforementioned edge.

It is well known in this art that pulley housings, when made in the ordinary manner create an unusual amount of waste material 40 which adds to the manufacturing cost and will ultimately in competition lead to the abandonment of said forms of pulley housings which have created a manufacturing cost greater than the selling price will support. 45 It is therefore one of the prime objects of this invention to provide a pulley housing which may be made up in a new and novel manner from stock of uniform width and without creating an appreciable amount of waste. 50 The preferred form of the pulley shown in

the accompanying drawings embodies the invention.

Figure 1 is a side elevation of a window pulley made in accordance with the invention.

Fig. 2 is a similar view of the opposite side thereof.

Fig. 3 is a top plan view of the pulley.

Fig. 4 is an edge view of the same.

Fig. 5 is a vertical central section through the pulley taken along line V—V of Fig. 1, and

Fig. 6 is a diagrammatic view showing the blank from which the pulley is being formed.

With specific reference to the parts of the window pulley illustrated in the accompanying drawings, wherein like reference characters refer to similar parts throughout the several views, the numeral 8 designates a wheel of ordinary construction over which may pass the window cord not here shown when the pulley is in the operative position.

This wheel 8 is supported within a housing 10 by a shouldered pintle 12 which serves both as a means for securing the housing together as well as a support for rotatably mounting the wheel 8. Housing 10 for wheel 8 is preferably formed of two parts, side 14 and a side 16. Each side may have a boss 18 pressed outwardly about the pintle 12 to lend rigidity and dome shaped top and side edges are closed along the seam 20 which may be fused by spot welding as at 22 to more securely hold together the sides 14 and 16. The lower edge of housing 10 is open for the passage of the window cords and in constructing an overhead pulley this lower open edge projects into a slot or similar opening formed in the head plate 26 of the ordinary window frame.

It is desirable to support housing 10 and fasten it in place as illustrated in Fig. 4 and in the manufacture of such structures it is desirable to use screw setting machines to drive the screws which hold the window pulley in place. To fulfill this requirement, yet to manufacture a pulley housing without additional expense by wasting material, a novel method of forming the housing has been conceived which consists in first striking out

blank 28 such as shown in Fig. 6 from which is made the two sides 14 and 16 of housing 10, to present a foot 30 long enough to receive the fastening means. Foot 30 is struck from 5 the blank to take material from both sides and at a predetermined point in the manufacture of the housing the two sides 14 and 16 are cut apart along line 32 which leaves foot 30 ready to be bent to a position as shown in 10 Figs. 3 to 5 inclusive where it lies in a plane spaced inwardly from the open edge of housing 10.

In this manner foot 30 has a projected length greater than the distance it lies inwardly from the opposite edge of housing 10. 15 Naturally the notch 34 from which part of the material for foot 30 was taken remains in side 14 but does not weaken the housing in any manner whatsoever. The angled sides 20 36 of foot 30 permits leaving sufficient stock in side 14 to form the pair of feet 38 from side 14 as shown in Fig. 2. These feet 38 lie in the same plane as foot 30 and all of the feet are preferably strengthened against dis- 25 torsion along the line of bend by the embossed ribs 40 which may be pressed into the material during the manufacture. As shown, each of the feet 38 may have an angled side 42 which allows for the economies in manu- 30 facture as hereinbefore set down. The notch 34 extends inwardly to a point on the plane extending between the lower sides of feet 38 which insures a complete closing when the window pulley is in place. After the lower 35 portion of the housing 10 has been positioned in opening 24 a screw or similar fastening means 44 may be driven through hole 46 to secure the device in place.

Thus it is seen that an extremely efficient 40 and cheaply constructed window pulley housing may be formed when practicing this invention and while the specific design is highly important, it is desired to be limited in practicing this invention only by the scope of the 45 appended claims.

What is claimed as new and desired to be secured by Letters Patent is:

1. A window pulley comprising a wheel, 50 a housing for the wheel and a plurality of supporting feet formed from the sides of the housing and disposed perpendicularly thereto, one of the sides having a pair of spaced apart feet, the other side having a single foot of greater projected length than either of 55 said feet of the pair and a hole formed through said single foot all of said feet being in a common plane parallel with the axis of said wheel.

2. A window pulley comprising a wheel, 60 a housing for the wheel, a pair of supporting feet formed from one side of the housing, a single foot of relatively greater length formed from the other side of the housing and a hole formed through said longer foot 65 adjacent the outer edge thereof and a diag-

onal rib formed in said housing to extend from the edge of said feet to its adjacent side wall.

3. A window pulley comprising a wheel, 70 a housing for the wheel, a pair of spaced apart supporting feet formed from one side of the housing, a single foot of relatively greater length and width formed from the other side of the housing, said feet all being disposed in a plane spaced inwardly from one edge of said housing, the projected length of 75 said single foot being substantially greater than the distance from its point of juncture with the housing to the aforesaid edge thereof.

4. A window pulley comprising a wheel, 80 a housing for the wheel, a pair of spaced apart supporting feet formed from one side of the housing a notch formed in the housing side extending inwardly from one edge thereof to a point between said pair of feet, a foot 85 formed from the other side of the housing, a notch formed in said side extending from the foot to the edge thereof, said foot having a projected length substantially equal to the combined depth of both of said notches. 90

5. A window pulley comprising a wheel, 95 a housing for the wheel, a pair of spaced apart supporting feet formed from one side of the housing, a single foot of relatively greater length and width formed from the other side of the housing and a hole formed through said foot adjacent the projected edge thereof, the extended plane of each side of the single foot intersecting one of the pair of feet respectively whereby to afford a three 100 point support for said housing, all of said feet being disposed in a plane at right angles to the plane of the wheel and spaced inwardly from one edge of the housing.

In testimony whereof I hereunto affix my 105 signature.

ROY E. HAMILTON.
